UNITED STATES PATENT OFFICE.

JOHN JENSEN, OF ROCKFORD, ILLINOIS, ASSIGNOR TO WHITNEY METAL TOOL COMPANY, OF ROCKFORD, ILLINOIS, A CORPORATION OF ILLINOIS.

ANGLE-IRON NOTCHER.

Application filed April 21, 1924. Serial No. 707,855.

To all whom it may concern:

Be it known that I, JOHN JENSEN, a citizen of the United States, residing at Rockford, in the county of Winnebago and State of Illinois, have invented a certain new and useful Angle-Iron Notcher, of which the following is a specification.

The invention relates to a means for forming V-shaped notches in one wall or leg of an angle iron bar to facilitate the formation of a right angle bend therein producing a mitre joint.

The general object of my invention is to produce an angle iron notcher which is capable of easy and rapid manipulation whereby effectually to form notches of the character indicated.

Machines heretofore employed for this purpose have not given satisfactory performance for the reason that the desired relative positions of the work and the punching or notching tool have not been properly maintained. This is due to the fact that in the manufacture of angle irons there is necessarily formed at the apex of the inner angle a fillet which in the notching operation induces or promotes a tendency in the cutting tool, riding upon the fillet, to move away from the vertical wall or leg of the angle. The result is that the apex of the notch when formed is spaced outwardly from the inner face of the vertical wall of the angle, and it becomes difficult, if not impossible, to produce a clean sharp bend in the bar.

It is a special object of my invention to provide a construction which insures that the proper relationship between the work and the cutting or punching tool shall be maintained notwithstanding the tendency of the fillet in the angle to disturb this relationship.

Figure 1 of the drawings is a fragmentary perspective view of an angle iron notcher constructed in accordance with my invention.

Fig. 2 is a fragmentary central vertical sectional view through the machine.

Fig. 3 is a horizontal section taken approximately in the plane of line 3—3 of Fig. 2.

Fig. 4 is a perspective view of an angle iron bar illustrating the manner in which the bar is notched to the proper depth.

The machine comprises a base 7 having a

plurality of lugs 8 whereby it may be rigidly secured in position upon a suitable support. Seated centrally of the base I provide a die block 9 having a triangularly shaped opening 10 therein with cutting edges 10^a and a rear guiding edge 10^b for a cutting tool or punch 11 in a manner to be presently described.

Rising from the rear edge of the base 7 is a bracket 12 reinforced by a web 13 and upon this bracket is carried a head 14 in which is mounted the operating means for the punch 11, the latter being suitably supported upon the lower end of a spindle 15 forming part of such operating means. Inasmuch as any suitable form of means may be employed for operating the punch I have deemed it unnecessary to illustrate the construction in detail. Suffice it to say that the spindle has in the present instance a helical groove therein with which, and a similar groove provided in the head, a series of bearing balls coact in the operation of a lever 16 on the spindle to raise and lower the punch 11.

The bracket 12 extends forwardly to a point near the forward edge of the base 7 and to resist upward strain upon the bracket incident to the punching operation, its forward edge is in the present instance secured to the base by means of a pair of opposite side members 17.

The punch 11 is in the form of a triangular head providing upwardly and rearwardly inclined cutting edges 11^a adapted to coact with the cutting edges 10^a in the die block. At its rear edge the cutting head 11 has integral therewith a depending guide member 11^b adapted to coact with the guiding edge 10^b of the die block. Below the die block the base has an opening 18 into which the guide member 11^b may project and through which the punched-out portions of the work may pass.

The work A as will be understood, is positioned on the base 7 with the leg or wall to be notched placed over the die block 10 and beneath the cutter head 11, and with the other leg or wall of the angle positioned forwardly and occupying an upright position. The work is held with the inner face of its upright wall against the apex of the cutter head 11 as shown clearly in Fig. 2 by means of an adjustable stop 19. This stop may be of any suitable construction. Herein it is

in the form of a block or bar interposed between the members 17 at the forward edge of the base and held down upon the base by pins 20 carried by said members 17. At its 5 forward edge the bar has a downwardly extending portion or lug 21 in which is journaled a screw 22 which is screw-threaded into the base, being suitably held against longitudinal movement in said lug. The 10 screw it will be observed constitutes an adjusting means for varying the position of the stop to accommodate varying sizes of work.

Referring now to Fig. 2 it will be seen 15 that the guide member 11^b is of such length that it engages with the guiding edge 10^b of the die block substantially before the cutting operation commences, and with the work firmly held against forward movement, 20 that is to say, in a direction away from the cutting tool by the stop 19, this depending guide member 11^b serves to maintain the work and the cutting tool in proper relation notwithstanding the tendency of the fillet 25 (shown at *a*) to disturb this relationship.

I have thus produced a notching means 30 for angle iron bars which is capable of easy and rapid operation to effectually perform the work for which it is intended and which 35 from a structural aspect is of a very rugged character.

I claim as my invention:

1. A means for forming mitre notches in 35 angle iron bars comprising, in combination, a base, a head supported above the base, a punching tool depending from said head and mounted for up and down movement, said base having an opening therein below said tool and a die block over said opening providing cutting edges adapted to coact with 40 the cutting edges of the tool and also a guiding edge, said tool having a depending portion adapted to engage with said guiding edge, and means for holding work positioned 45 between the tool and the die block against movement in a direction away from the tool, the arrangement being such that said guide member engages with its coacting edge in 50 the die block substantially before the beginning of the cutting operation.

2. An angle iron notcher comprising, in 55 combination, a base having a die block seated therein, a cutting or punching tool angular in form adapted to coact with the die block to produce a V-shaped notch in one wall of the angle iron bar interposed therebetween, means for holding said bar against movement in a direction away from the cutting tool, and means coacting with the base and 60 operable to hold the cutting tool against movement in the opposite direction.

3. An angle iron notcher comprising, in 65 combination, a base having an aperture

therein, means for supporting above the base a cutting tool adapted for movement 65 through the aperture in the base, means for holding an angle iron bar against movement on the base in a direction away from the tool, and guiding means acting between the tool and the base and operable to resist movement 70 of the tool in the opposite direction.

4. The combination of a base having an opening therein, a bracket rising from the rear edge of the base, a head carried by said bracket, a punching tool, a tool-carrying 75 spindle mounted in the head and operable to raise and lower the tool, said tool being adapted to cut a notch in a piece of work interposed between it and the base, a pair of straps connecting the forward edge of the 80 base with said head, and means for holding the piece of work against movement away from the cutting tool comprising a bar resting upon the inner forward edge thereof, and means carried by said straps for guiding 85 said bar.

5. The combination in a tool of the character described of a base, a stop against which the outer face of the upright wall or leg of 90 an angle iron bar is adapted to engage, and cutting means for forming a V-shaped notch in the other wall or leg of said bar while held by the stop, said stop being adjustable in the base toward and from the cutting means.

6. The combination in a tool of the character described of a base, a stop against which the outer face of the upright wall or leg of 95 an angle iron bar is adapted to engage, cutting means for forming a V-shaped 100 notch in the other wall or leg of said bar while held by the stop, said stop being adjustable in the base toward and from the cutting means, and a guide member associated with the cutting means operable to hold the 105 tool against movement in a direction away from said stop.

7. A means for cutting V-shaped or mitre notches in an angle iron bar having means 110 for supporting the work including a stop member and cutting means comprising a tool angular in form and positioned with its apex adjacent said stop, the arrangement being such that an angle iron bar to be cut is positioned with its horizontal wall or leg 115 beneath the tool and with its vertical leg held by said stop against the apex of the tool, and a member depending from the tool and coacting with the base prior to the commencement of the cutting operation so as to 120 hold the tool against movement in a direction away from the stop.

In testimony whereof, I have hereunto affixed my signature.

JOHN JENSEN.
